INVENTOR-

William Hughes
By his Attorney
Nelson M. Howard

UNITED STATES PATENT OFFICE.

WILLIAM HUGHES, OF TAUNTON, MASSACHUSETTS, ASSIGNOR TO UNITED SHOE MANUFACTURING CORPORATION, OF PATERSON, NEW JERSEY, A CORPORATION OF NEW JERSEY.

ORNAMENTAL EYELET AND ARTICLE ORNAMENTED THEREWITH.

Application filed March 27, 1928. Serial No. 265,180.

This invention relates to eyelets, and more particularly to eyelets whose ornamental appearance contributes substantially to their utility. It is herein illustrated in its application to a shoe, although it is to be understood that it is not limited to shoes.

Eyelets as heretofore made have been provided with solid flanges that are arranged to lie (excepting invisible eyelets) on the outer surface of a shoe upper, belt or other article of manufacture to which they may be applied. It is desirable that eyelets applied to many articles of manufacture should have an ornamental effect. This is commonly the case with eyelets applied to shoes and belts, as to which there is a considerable demand for fancy eyelets and for novel ornamental effects produced thereby.

Accordingly an object of this invention is to provide an improved eyelet adapted to produce a novel and artistic effect when applied to a shoe, belt or other article.

A novel feature of the invention consists in an eyelet having a flange provided with one or more ornamental perforations through which a panel or panels of the eyelet-receiving material of a shoe, belt or other article will be visible when the eyelet is applied to such material. Thus, while the perforations produce a novel ornamental effect, the panels of eyelet-receiving material visible through said perforations accentuate that effect. The composite article thus produced is another feature of the invention. The novel ornamental effect thus produced may be supplemented by contrastive effects according to the colors and finishes of the eyelet flanges and of the eyelet-receiving materials against which they lie.

Again, the perforations in the eyelet flanges cause the flanges to appear lighter and more graceful than they would otherwise. Accordingly, the eyelets may be provided with relatively wide flanges without offending the sense of artistic proportion.

The invention also provides for another novel ornamental effect which is obtained by clenching the eyelets tightly in eyelet-receiving material which is somewhat resilient or compressible. As to this aspect of the invention, a novel feature consists in an article of manufacture comprising resilient eyelet-receiving material provided with a tightly

clenched eyelet the flange of which is arranged on a surface of the material and has one or more ornamental perforations into which panels of the eyelet-receiving material protrude and in which they simulate the appearance of inlays. This effect dispels the appearance of thickness of the flange which, as shown, is flat and as thin as it may be consistently with the strength required of it, so that the panels will appear to be, and in some cases will actually be, flush with the outer surface of the flange.

Referring to the accompanying drawings,

Fig. 1 is a frontal perspective view of a shoe quarter fitted with eyelets embodying the present invention;

Fig. 2 is a cross-section, enlarged to slightly more than three diameters, of one of said eyelets clenched in a portion of a shoe upper;

Fig. 3 is a face view of a portion of a shoe quarter fitted with such eyelets, the area representing the quarter being stippled to exemplify a visual contrast between the eyelets and the material to which they are applied; and

Fig. 4 is a perspective view of an unclenched eyelet of the type shown in the other figures, the scale being about equal to that of Fig. 2.

The upper of the shoe illustrated in Fig. 1 comprises quarters 10, 10 formed with edges 12, 12 to provide a lacing slit or opening. Each quarter is provided with a row of eyelets 14 adjacent to its edge 12 to receive a lacing. Fig. 2, the scale of which is enlarged to about three diameters, illustrates a typical example of the eyelet-receiving material of a man's shoe, the several layers of material therein shown being an outer layer 16 of leather, an eyelet stay 18 of woven fabric and an inner facing or lining 20 of leather. It is to be understood, however, that the present invention is not limited to the make-up or combination of layers 16, 18 and 20 of the eyelet-receiving materials shown in Fig. 2.

The novel eyelets shown in the drawings are made of uncoated ductile metal, for example, brass, but for certain desirable contrasts between eyelets and eyelet-receiving material the eyelets may be provided with any one of a variety of finishes such as a coating of nickel-plate or enamel of any desired color. In the illustrated example each

eyelet comprises a square barrel 22 and a circular flange 24, the flange having four ornamental perforations 26 of segmental shape symmetrically arranged in a circular series and shaped to conform to and harmonize with the square configuration of the barrel and the circular configuration of the flange. The invention is not limited, however, to the configurations shown, nor to the illustrated 10 shape or arrangement of the perforations 26.

The barrels 22 are inserted through the eyelet-receiving material from the outer side of the latter so that the flanges 24 will lie on the outer or obverse surface 28 of said 15 material. Thus, when the eyelets are applied to materials of the kinds above mentioned, with the degree of pressure commonly applied by eyelet-inserting machines, the inner ends of the barrels will be clenched tightly 20 as shown at 30 in Fig. 2 and the flanges 24 will be embedded in the surface 28, since the perforations 26 permit the flanges to sink appreciably into said surface.

Panels 32 of the eyelet-receiving material 25 are not only visible through the perforations 26 but they protrude more or less into said perforations according to the pressure with which the eyelets are clenched and according to the resilience or softness of the eyelet- 30 receiving material that engages the flanges. However, whether the degree of protrusion is much or little, the protrusion dispels the appearance of thickness of the flanges and causes the panels to simulate inlays. The 35 flanges 24 of the illustrated eyelets are flat and as thin as they may be consistently with the strength required of them. Consequ- 40 ently, they do not project appreciably above the surface 28 when they are applied with the degree of clenching pressure commonly used with non-perforated eyelets. In some cases, for example, when eyelets of this type are applied to softer materials such as velvet, 45 suede and kid, the panels 32 may protrude to, and even beyond, the planes of the obverse surfaces of the flanges 24. The perforations 26 reduce the area of contact between the flanges and the contacting material so that a 50 given degree of clenching pressure will cause deeper embedding of the flanges than that possible with unperforated flanges of corresponding size.

The ornamental effects of the panels 32 upon the flanges 24 are susceptible of many 55 variations and may be accentuated much or little, as desired, by using eyelets and eyelet-receiving materials of contrasting visual characteristics. In the example shown, the layer 16 of leather has a dull finish (represented by stippling in Fig. 3) while the obverse surfaces of the flanges 24 have a bright shiny finish. Moreover, there is a chromatic 60 contrast between the surface 28 and the brass of which the eyelet is made, and the orna-

mental effects of the panels 32 within the 65 perimeters of the flanges 24 are due in part to the contrasting colors and in part to the contrasting finishes of the flanges and the eyelet-receiving material.

The perforations 26 in the illustrated eyelets are arranged to provide a conventional 70 design in which the individuality of the perforations is prominently displayed. It is, therefore, desirable that the eyelets be inserted in such a manner that the perforations 75 will be located in predetermined relation to some edge, line or configuration of the eyelet-receiving material. For example, in the case of a shoe of the type illustrated 80 it is preferable to insert the eyelets so that the perforations will be uniformly arranged relatively to the edges 12 of the lacing slit. Consistently with this consideration the non- 85 circular configuration of the barrels 22 may be advantageously used to insure uniform disposition of the perforations by employing an eyelet-inserting machine equipped with an eyelet-engaging spindle of noncircular 90 cross-section conforming to the configuration of the interior of the barrels 22. A typical example of a noncircular spindle suitable 95 for dealing with this problem is illustrated in U. S. Letters Patent No. 1,008,036 granted to me November 7, 1911. As shown in that 100 patent the spindle is provided with an eyelet-engaging portion of square cross-section and is prevented from turning relatively to the pressure-applying member or setting tool with which it is combined, so that an eyelet 105 having a barrel of square cross-section will be maintained by the spindle in a predetermined position when it is inserted into the eyelet-receiving material.

Having described my invention, what I 110 claim as new and desire to secure by Letters Patent of the United States is:

1. An eyelet having a barrel and a flange 115 provided with one or more ornamental perforations through which panels of eyelet-receiving material will be visible when the eyelet is inserted in such material.

2. An article of manufacture provided 120 with one or more clenched eyelets each having a flange lying against a surface of the eyelet-receiving material of the article, said surface and said flange having contrasting 125 appearances and said flange having one or more ornamental perforations through which panels of the eyelet-receiving material are visible to accentuate the ornamental effect of said perforations.

3. An article of manufacture having eyelet-receiving material provided with one or 130 more tightly clenched eyelets the flanges of which lie against a surface of said material and are thin and flat, the flange of each eyelet having one or more perforations through which ornamental panels of the eyelet-receiving

ing material are visible and appear to be substantially in the plane of the outer face of the flange.

4. An article of manufacture comprising eyelet-receiving material having a resilient surface and provided with a tightly clenched eyelet the flange of which is arranged on said resilient surface, said flange having one or

more ornamental perforations into which panels of the eyelet-receiving material protrude and in which they simulate the appearance of inlays. 10

In testimony whereof I have signed my name to this specification.

WILLIAM HUGHES.
